OF NEW YORK, N. Y., A CORPORATION OF NEW YORK.

TRACKER ADJUSTMENT AND TRANSPOSING APPARATUS.

1,206,996.

Specification of Letters Patent.

Patented Dec. 5, 1916.

Application filed June 21, 1916. Serial No. 104,891.

To all whom it may concern:

Be it known that I, WALTER R. CRIPPEN, a citizen of the United States of America, residing at New York city, county and State of New York, have invented a new and useful Tracker Adjustment and Transposing Apparatus, of which the following is a specification.

My invention relates to an apparatus designed to adjust the tracker mechanism of a mechanical music playing instrument whereby the ducts therein may be caused to properly register with the perforations in a music sheet, and also whereby said tracker mechanism may be shifted at any time for transposing the key. These ends I attain by the use of very simple, durable and effective mechanism which will invariably operate with certainty and accuracy.

In the accompanying drawings: Figure 1 is a front view with certain parts broken away. Fig. 2 is a side view. Fig. 3 is a section on the line 3—3, Fig. 1.

1 represents a tracker having the usual ducts therein.

2—3 conventionally represent music rolls designed to draw a sheet of perforated music across the tracker 1. The rolls 2—3 may be mounted in any suitable way on the usual spool box or frame. The tracker and said rolls are relatively adjustable, and in the simplest embodiment of my invention I prefer to shift the tracker 1 when it is desired to effect said adjustment. To that end I have shown in the accompanying drawings, an arrangement whereby the shifting mechanism is applied to the tracker 1 instead of to the rolls.

4—4 represent tracker guides.

5 is a lever fulcrumed at 6 and pivotally connected at 7 intermediate its length to a second lever 8. The second lever 8 is connected at one end to the tracker 1, as by a link or rod 9. The pivot point 7 is made adjustable in any suitable way as by a rod 10 leading from the lower end of lever 5 to an operating handle 11 which may be shifted by hand for the purpose of moving the lever 5 and thereby the pivot point 7. The lower end of the rod 8 is manually adjustable on a notched rack 12 or equivalent device, the notches therein being so spaced as to give a predetermined or step by step adjustment to said tracker.

13 is a manually operable arm which is connected by a suitable bar with the lower end of lever 8, which arm has a snap engagement with the rack 12.

14 is a friction spring which constitutes one suitable means for holding the lever 5 in any adjusted position.

15 is a spring which serves to hold the arm 13 in engagement with the rack 12.

Operation: If it is desired to adjust the tracker 1 slightly, for the purpose of causing the ducts therein to register properly with the perforations in a note sheet traveling over the same, the operator shifts the rod 10 to any desired degree and thereby moves the levers 5—8 sufficiently to shift the tracker to the desired position. If now at any time it is desired to transpose the key in which the music is being played, the operator has simply to shift the arm 13 on the rack 12, the notches therein being so spaced that the shifting of the arm 13 will move the lever 8 and tracker 1 to the left or right a distance sufficient to bring each one of the ducts therein into accurate alinement with the next row of perforations to the right or left in the note sheet, thereby transposing the key. Any suitable number of notches may be provided in the rack 12. Heretofore it has been common to effect adjustment by shifting one or the other of the rolls 2—3, but such a method is undesirable because it involves a twisting or distortion of the music sheet. It is, therefore, preferable to cause the rolls 2—3 to remain in proper alinement and to shift both rolls 2—3 relatively to the tracker, or vice versa, for the purpose of securing said adjustment. In the present instance I have selected the tracker as the movable element for securing the relative adjustment, and I have likewise preferably selected the same means for transposing adjustment, although in a broad sense, it should be understood that it is this relative adjustment that is sought, and that it matters not whether the music rolls are moved or the tracker is moved for securing said adjustment and transposition. I may also modify the particular construction and method of connecting the over-

lapping elements 5—8 without departing from the spirit and scope of the invention. I may also employ any suitable means for holding the parts in their various adjusted positions.

What I claim is:

1. In an apparatus of the character described, a tracker mechanism, music roll mechanism parallel thereto, one of said mechanisms being longitudinally adjustable relatively to the other, adjusting means therefor comprising two coöperating manually controllable elements, one of said elements being shiftable to variable degrees, the other being shiftable to predetermined degrees without shifting the first element.
2. In an apparatus of the character described, a tracker mechanism, music roll mechanism parallel thereto, one of said mechanisms being longitudinally adjustable relatively to the other, adjusting means therefor comprising two coöperating manually controllable elements, one of said elements being shiftable to variable degrees, the other being shiftable to predetermined degrees without shifting the first element, the movement of said first element automatically varying the starting position of said second element.
3. In an apparatus of the character described, a tracker mechanism, music roll

mechanism parallel thereto, one of said mechanisms being longitudinally adjustable relatively to the other, adjusting means therefor comprising two coöperating manually controllable elements, one of said elements being adjustable to variable degrees, the other being adjustable to predetermined degrees and independently of the first, the movement of the first automatically varying the starting position of the second, said adjusting means including two overlapping levers with a relatively stationary fulcrum for one, the second lever being fulcrumed on the first lever.

4. In an apparatus of the character described, a tracker mechanism, music roll mechanism parallel therewith, one of said mechanisms being longitudinally adjustable relatively to the other, adjusting means comprising a lever fulcrumed on a relatively stationary support, and another lever fulcrumed on the first lever, manually operable means for swinging the first lever to variable degrees within its range of movement, a connection between the second lever and the part to be moved, and manually operable means for swinging the second lever to certain predetermined fixed positions and arranged to hold the same in any one of said fixed positions.

WALTER R. CRIPPEN.
